UNITED STATES PATENT OFFICE

116,270

DESIGN FOR A PORTABLE RADIO RECEIVER

Harold C. Mattes, Chicago, Ill., assignor to Belmont Radio Corporation, Chicago, Ill., a corporation of Illinois

Application May 10, 1939, Serial No. 84,917

Term of patent 3½ years

To all whom it may concern:

Be it known that I, Harold C. Mattes, a citizen of the United States, residing at Chicago, in the county of Cook and State of Illinois, have invented a new, original, and ornamental Design for a Portable Radio Receiver, of which the following is a specification, reference being had to the accompanying drawing, forming part thereof, in which:

Fig. 1 is a top plan view of a portable radio receiver showing my new design;

Fig. 2 is an elevational view of one side thereof;

Fig. 3 is an elevational view on a reduced scale of the other side thereof; and

Fig. 4 is an elevational view of one end thereof with the handle broken away for convenience of illustration. The other end thereof is identical in appearance.

The characteristic features of my new design are shown in solid lines in the drawing.

I claim:

The ornamental design for a portable radio receiver, substantially as shown and described.

HAROLD E. MATTES.
